[57] ABSTRACT

A valve for controlling the crankcase ventilation for an internal combustion engine constructed to be much less expensive than prior valves but to have better performance characteristics due to a unique flow control.

CRANKCASE VENTILATING VALVE

SUMMARY OF THE INVENTION

This invention is in the field of crankcase ventilating valves for use with internal combustion engines and is concerned with a valve structure for controlling the air flow for ventilating the crankcase of an internal combustion engine.

A primary object is a crankcase ventilating valve which provides positive crankcase ventilation with smooth even flow through the valve.

Another object is a valve structure of the above type which is less expensive than prior units but, at the same time, is more uniform in flow characteristics.

Another object is a valve structure of the above type which avoids any fluttering or burbling.

Another object is a valve structure of the above type in which the housing is entirely of plastic with a metering pin of metal and a metal orifice which prevents contact with the housing so the plastic will not wear.

Other objects will appear from time to time in the ensuing specification and drawings:

BRIEF DESCRIPTION OF THE DRAWINGS

FIG. 1 is a side view of the valve;

FIG. 2 is an end view;

FIG. 3 is a sectional view taken on line 3-3 of FIG. 2, with parts in full;

FIG. 4 is an end view of the orifice; and

FIG. 5 is a section along line 5-5 of FIG. 3.

DESCRIPTION OF THE PREFERRED EMBODIMENT

In FIG. 1, the valve or metering element has been indicated generally at 10 and includes a body or valve housing composed of two main elements. The first 12 is what is referred to as the lower element and the second 14 as the upper element. This is not to say that one is above the other and, in fact, the device may be used and operated sideways, as in FIGS. 1 and 3, or in any position. The terms top, bottom, upper, lower, etc. may be used herein merely for purposes of designation and orientation, and it should be understood that the valve will operate satisfactory in a horizontal or upside down position, vertical or otherwise; in fact, in any position.

The lower element 12 includes a generally cylindrical socket 16 stepped at 18 with an offset outlet or branch 20 on one side. The step 18 provides an annular shoulder 22 against which a flow orifice 24 is positioned, which is in the nature of a washer.

The upper element 14 has a generally cylindrical exterior with a pilot portion 26 at one end shaped and dimensioned to fit into the recessed portion 18 of the lower element. Element 14 has an opening or channel 28 through it of a diameter to accept a pin 30. The inlet end 32 of element 14 is reduced to a somewhat smaller orifice 34 to keep the pin in and provides a backfire shoulder 36 as explained hereinafter. Otherwise, the interior of the channel 28 may be considered to have a constant diameter. The dimensioning is such that the forward surface 38 of the pilot portion 26 abuts the orifice or washer 24 before the enlarged shoulder 40 hits the end flat face 42 on the lower section. The two parts may be made entirely of plastic, for example nylon, and the abutting surfaces 40 and 42 may be glued or heat sealed or the cylindrical surfaces, as at 18, may have a shrink fit by heating the projecting or outside end of the main body section and allowing it to cool around the pilot portion 26 which, for this purpose, might be slightly oversize in O.D. In any event, it is considered important that the projecting surface 38 of the pilot portion firmly abut the washer 24 and hold it against the shoulder 22 in a firm, tight, gripping contact when the units are secured.

The pin 30 may be of metal, such as steel, and may have a shank 44 with a square head 46 and seating taper 48 at one end and a tailored or contoured portion 50 at the other terminating in a projecting guide or finger 52, the portion 50 being tailored to the blowby characteristics of the engine. The

pin may be surrounded by a generally tapered spring 54 which, at one end, engages the head 46 and at the other engages part of the washer 24.

The orifice 24 may be in the form of a metal washer with an outer annular flange 56 merging smoothly into a miter 58 directed downstream, in the direction of air flow, followed by a cylindrical horn 60 which projects a predetermined distance downstream into the channel or socket 16 of the lower body member.

10 The exterior of both the inlet and the outlet may be shaped, as at 62, to accept a hose connection. While the outlet 20 has been shown on the side, it might be on the end wall 12 in a straight-through unit.

15 The use, operation and function of the invention are as follows:

The valve is specifically intended to be used for ventilating the crankcase of an internal combustion engine and is positioned in a hose or line connection between the crankcase and the inlet manifold, the object being that when the vacuum in

20 the inlet manifold is high, as at low loads, the vacuum will be communicated through opening 20 to draw the tailored pin 30 down into the orifice 24 thereby restricting or reducing the flow of crankcase vapor or blowby from the crankcase to the inlet. But at high loads, when the vacuum in the inlet manifold

25 is least, the pressure differential across the valve will be the least, which will allow the spring to move the pin back to generally the position shown in FIG. 3 opening up the orifice and allowing the greatest flow. All of this is old and well known.

30 Prior valves of this type have been made entirely of metal which has the disadvantages of expense, wear, and corrosion.

In the present structure, the housing itself, including both parts 12 and 14, is made entirely of plastic. And while nylon 35 has been mentioned as a possibility, it should be understood that any suitable plastic may be used, for example polyvinylchloride, polystyrene or the like. At the same time, the pin 30 is of metal so that its exterior will not change shape in use which might otherwise happen when the unit is vibrated and banged around.

40 The orifice 24 is in the form of a washer, preferably of metal, again so that its flow characteristics will not change in use. The washer or orifice is rigidly held between the two housing parts and is specifically shaped to prevent any burbling or fluttering in the air flow pattern through the valve. It will be realized that the air flow will be controlled by the exterior of the pin and the interior of the orifice, the housing itself serving merely as a conduit and enclosure.

45 The operative end of the pin, referring to the tailored part 50 and shank 44, are drawn from time to time into the orifice structure, depending upon the engine's operating condition so that a greater or lesser cross section will be presented to and inside of the orifice. The miter 58 of the orifice will prevent or eliminate any eddy currents in the air flow which might otherwise occur at a sharp edge orifice. Following this is the cylindrical horn 60 which insures that the air flow does not drag or break away from the wall surface as it goes through the orifice. Further, the opening through the washer or orifice may be

50 considered to be in the form of a bell which may be extruded or punched so that the inside diameter, which determined air flow, can be accurately controlled. The flow pattern through the variable annular space between the exterior of the pin and the interior of the washer should be smooth and non-turbulent at all loads on the engine. In the orifice itself and the tubular horn 60, there should be no contraction of the air flow and the orifice should flow full at the downstream end. And this cannot be accomplished with a sharp edge washer or orifice. The horn 60 with the miter 58 bounding the entrance guarantees a

55 non-fluttering flow pattern which, if it were to occur, can have a fluttering or chattering effect on the pin itself due to its suspended condition in the housing. Thus, the air flow is greatly stabilized.

60 In the event of backfire which will create a greater pressure in what would otherwise be the outlet 20, the pin may move to

the right in FIG. 3 so that the taper 48 will seat against the annulus 36 thereby preventing any flames or sparks from getting into the crankcase.

One of the advantages of the present structure is that while the housing is made entirely of plastic and, therefore, inexpensive, the operative parts, the pin and orifice, are of metal. And any contact between them due to vibrations or handling will not result in wear or nicks on the housing.

While the preferred form and several variations have been suggested, it should be understood that suitable additional modifications, changes, substitutions and alterations may be made without departing from the invention's fundamental theme.

I claim:

1. For use in an engine crankcase ventilating system, a metering valve adapted to be positioned in a conduit between the crankcase and the inlet manifold, the valve including a two-part housing with a passage through it for the flow of crankcase vapors, a pin having a small end in the passage in the housing having an exterior which is tailored to the blowby characteristics of the engine, a spring biasing said pin, and an orifice in the housing in the form of a washer having a passage therethrough surrounding the small end of the pin when the

pin is in its free state and having an outstanding flange held between the two parts of the housing and the passage through said orifice being tapered and extending downstream to form a cylindrical flow regulator defining an annular flow orifice with the exterior of the pin, the various cross sections of the pin being less than the passage through the orifice and flow regulator in all normal positions of the pin.

2. The structure of claim 1 further characterized in that the two parts of the housing are socketed together, one part being 10 piloted into the other, with the opposed surfaces clamping the outstanding flange on the orifice between them in a tight joint.

3. The structure of claim 1 further characterized in that the spring surrounding and positioning the pin, at its large end, engages the outward flange on the orifice.

15 4. The structure of claim 1 further characterized by and including an inlet and outlet at each end of the passage through the housing, the inlet being aligned with the longitudinal direction of movement of the pin and the outlet being disposed at generally 90° thereto.

20 5. The structure of claim 1 further characterized in that the housing is made of plastic and the pin and orifice are made of metal.
